UNITED STATES PATENT OFFICE.

ANTON BECKER, OF COLUMBUS, OHIO, ASSIGNOR TO THE RALSTON STEEL CAR COMPANY, OF COLUMBUS, OHIO.

DUMPING-CAR.

995,214.

Specification of Letters Patent. Patented June 13, 1911.

Application filed May 20, 1910. Serial No. 562,535.

To all whom it may concern:

Be it known that I, ANTON BECKER, of Columbus, in the county of Franklin and State of Ohio, have invented certain new and useful Improvements in Dumping-Cars; and I do hereby declare the following to be a full, clear, and exact description of the invention, such as will enable others skilled in the art to which it appertains to make and use the same.

This invention relates to improvements in dumping cars,—one object of the invention being to provide a simple and efficient structure which can be converted from a gondola to a hopper bottom car and vice versa.

A further object is to construct the car in such manner that the hopper bottom shall be so divided longitudinally as to form two triangular hoppers at respective sides of the center girder, and to provide means located parallel with the center girder for operating the hopper doors.

A further object is to so construct a car having a centrally located hopper, as to provide connecting means between the bolsters in line with the draft sills and secured to the latter.

A further object is to provide simple and efficient means for mounting and manipulating the floor sections and side doors of a convertible dumping car.

With these objects in view the invention consists in certain novel features of construction and combinations of parts as hereinafter set forth and pointed out in the claims.

In the accompanying drawings, Figure 1 is a transverse sectional view, one half of which shows the arrangement of parts for a gondola car and the other half showing the arrangement for a hopper bottom car. Fig. 2 is a central longitudinal sectional view of the car showing the center girder in side elevation and the floor sections elevated when the hopper bottom is to be used for central discharge purposes. Fig. 3 is a plan view partly in section with the parts in position to form a hopper bottom car. Fig. 4 is a side elevation. Fig. 5 is an enlarged detail view, partly in section, at one corner of the car structure. Fig. 6 is an enlarged detail view, partly in section, showing the stakes at the center of the car and the relation of the side doors thereto, and Figs. 7

and 8 are detail views illustrating the side door construction.

1 represents a center girder which consists of a plate to the upper edge of which angle-bars 2 are secured and to the lower edge of said plate girder angle-bars 3 are securely riveted,—the lower flanges of said last mentioned angle-bars projecting laterally and their lower faces being in horizontal alinement with each other at the bottom of the plate girder 1.

At the center of the car, an inverted U-shaped cross-bearer 4 is located and comprises two members at respective sides of the center girder and secured at their inner ends to the latter,—the outer ends of the members of the U-shaped cross-bearer being secured to side sills 5. Each of these side sills is of the plate girder type and provided at the upper edge with an angle bar 6, the upper flange of which projects inwardly approximately in line with the top of the cross-bearer 4. The lower edge of each side sill has secured thereto, two angle-bars 7, the lower flanges of which constitute the base of the side sill.

To the outer faces of each member of the U-shaped cross-bearer 4, angle-bars 8 are secured and inclined downwardly and inwardly from the upper edges of the side sills and terminate an appreciable distance from the bottom of the center girder. To these inclined angle-bars 8, the inclined hopper plates 9 are secured and at the lower edges of these hopper plates, angle-bars 10 are located. Hopper doors 11 are hinged at their upper edges to the bars 10 at the lower edges of the hopper plates 9 and serve to close the outlets of the hopper between the lower edges of the hopper plates and the bottom of the center girder.

Transverse angle-bars 12 are secured to the inner faces of the respective members of the U-shaped cross-bearer 4 at the lower edges thereof and these angle-bars extend from one side sill to the other and under the center girder,—the respective ends of the transverse bar 12 being secured to the angle-bars 7 which constitute the bases of the side sills. The outer ends of the hopper plates 9 are secured to the inclined edges of the hopper ends 14 and the ends of the center girder are inclined in conformity with the inclination of the hopper ends. A plate 15 is secured to the base angles 3 of the center

girder and extends upwardly along the inclined ends of said girder and is secured to the latter by means of angle-bars 16. To this plate the inner side edges of the hopper 5 ends 14 are secured and said plate also affords means for securing draft sills 17 to the center girder. To assist in sustaining the side hopper plates 9 between the cross-bearer 4 and the hopper ends, triangular 10 braces 18 are disposed between said hopper plates 9 and the side sills 5, as clearly shown in Fig. 1. Each car bolster 19 comprises parallel diaphragms 20 at respective sides of the draft sills 17 and secured to said sills; 15 a compression member 21 secured to the lower flanges of said diaphragm, and a tension member secured to the top flanges of said diaphragms,—said tension member in the present instance consisting of a floor 20 plate 22 which extends from the end of the car to the end of the hopper, as shown in Fig. 2. Between the draft sills 17 and in line with the space between the bolster diaphragms, a bracket 23 is secured and provided with a socket for a king pin.

From the above construction it will be observed that the hopper is centrally located; that the center girder passes through the longitudinal center of the hopper and in 30 line with the draft sills, and that said hopper is divided by the center girder and the centrally located cross-bearer, into four smaller hoppers, each of triangular form and each provided with a door 11 for controlling the discharge of the contents of 35 said hoppers.

At each end of the hopper bottom, brackets 24 are located and to these brackets floor sections 25 are hinged and of sufficient 40 length to extend from the hopper bottom to the ends of the car structure or approximately to said ends,—said floor sections 25 being provided on their rear or under faces with angle-bars 26 which rest upon the floor 45 plates 22 when said bottom sections 25 are disposed in a horizontal position to form portions of the bottom of a gondola car.

When the floor sections 25 are in vertical positions, as shown in full lines in Fig. 2, 50 they will constitute the ends of the upper portion of the hopper,—the sides of said upper or body portion of the hopper car being formed by doors 27, as hereinafter explained. The doors 27 above referred to 55 are more properly speaking, floor sections 60 and are hinged at their outer edges to the side sill members. These floor sections 27 are provided on their inner or under faces with channel irons 28 and are adapted to 60 cover the hopper bottom as shown in Fig. 61 and aline with the floor sections 25 when the car is to be used as a gondola car.

Flanged side stakes 29 are secured to the side sills and at the ends of the U-shaped 65 cross-bearer, two flanged stakes (of Z-

shaped cross-section) are provided and between these Z-shaped stakes a suitable filler 30 may be secured as shown in Fig. 6. The upper ends of the side stakes at respective sides of the car are connected by continuous 70 angle-beams 31. Between the stakes 29, side doors 32 are hinged or pivotally connected at their upper ends to said stakes in proximity to the upper connecting beam 31 and the flanges of said stakes constitute 75 stops to limit the inward movement of the hinged side doors. Each side door is braced by means of channel bars 33 extending from the upper to the lower end thereof and all of the side doors 32 at each side of the car 80 may be connected together by means of angle-beams 34 secured at the lower edges of said doors,—said angle-beams being bent outwardly as shown at 35, Fig. 6, to avoid conflict with the side stakes.

The side doors 32 are maintained normally in their closed positions by means of chains 36 secured to the angle-beam 34 and, after passing through suitable holes 37 in the side sill, said chains are wound upon 90 a shaft 38 extending from end to end of the car and provided at each end of the car with a suitable lever 39 for turning it. It will ordinarily not be necessary to provide more than three such chains 36 for the side doors 95 at each side of the car and the central chain may if desired be wound on the shaft 38 where the latter passes through the central U-shaped cross-bearer 4. Any suitable means may be provided for locking the shaft 100 38 and it is apparent that when this shaft is unlocked, the side doors will be free to swing outwardly.

When the car is to be of the hopper bottom-type, the floor sections 27 will be raised to vertical position as shown at the right hand side of Fig. 1 and will be held in such position by suitable clamps or hooks 40 attached to the upper angle beams 31 which connect the upper ends of the stakes,—said floor sections being then disposed parallel with the hinged side doors and constituting the side walls of the body portion of the hopper car, the end walls being formed by the floor sections 25 when the latter are 115 raised to vertical position, as shown in Fig. 2. For the end floor sections 25, stops 41 are provided, as shown in Fig. 5.

Brackets 42 depend from the bottom of the center girder and in these brackets, a shaft 43 is mounted so as to be disposed immediately under said center girder. The hopper doors 11 are provided at their free ends with depending arms 44 and to the free ends of these arms chains 45 are attached. These chains are wound on the shaft 43, so that when said shaft is rotated, the doors at both sides of the center girder will be operated simultaneously. The shaft 43 is provided with a worm wheel 46, with 120 125 130

which a worm 47 meshes,—said worm being secured to a transverse shaft 48 mounted in suitable hangers 49 and 50 and provided at its end beyond one of the side sills of the car 5 with an angular portion 51 for the reception of a suitable operating device.

Any suitable means may be provided for normally locking the shaft 48 against rotation when the hopper doors are closed. It is 10 apparent that when the shaft 48 is unlocked, the hopper doors will open by reason of the weight of material thereon and that by rotating said shaft to cause the chains 45 to be wound on the shaft 43, the hopper doors 15 will be closed.

Having fully described my invention what I claim as new and desire to secure by Letters-Patent, is,—

1. In a dumping car, the combination with 20 side sills, a center girder provided with inclined ends, and a centrally located cross-bearer, of hopper plates, each secured at one end to the cross-bearer, hopper ends secured to the other ends of said hopper plates at 25 respective sides of the center girder, a plate secured to the bottom of the center girder and extending along the inclined ends thereof, and draft sills secured to said plate.

2. In a dumping car, the combination with 30 car sides and a center sill, of an inverted U-shaped cross-bearer secured to said car sides and center girder, hopper plates secured to said cross-bearer, hopper ends secured to the hopper plates and connected 35 with the center girder, and transverse angle-bars secured to the inner faces of the U-shaped cross-bearer at the lower edges thereof, said transverse angle-bars extending from one car side to the other and under 40 the center girder and secured to the bottoms of said car sides and center girder.

3. In a dumping car, the combination with 45 car sides, a center girder, and a centrally located cross-bearer secured to said car sides and center girder; hopper plates secured to the cross-bearer, hopper ends secured to the hopper plates and connected with the center girder, and brackets or braces disposed between the hopper plates and the car sides

intermediate of the cross-bearer and hopper 50 ends.

4. In a dumping car, the combination with framework and side stakes secured thereto, of side doors hinged at their upper ends between said side stakes, angle-beams secured 55 to the lower edges of the doors and connecting said doors, and means connected with said angle-beams for closing the doors and maintaining them closed.

5. In a dumping car, the combination with 60 side sills and transverse members, of side stakes secured to the side sills, side doors hinged at their upper ends between the side stakes, shafts mounted inside the side sills, means for operating said shafts, and chains 65 wound on said shafts, passing through the side sills and connected with said side doors.

6. In a dumping car, the combination with side sills and transverse members, of flanged side stakes secured to the side sills, side 70 doors hinged at their upper ends between said stakes, the flanges of said stakes constituting stops to limit the inward movement of said doors, a door operating shaft, angle bars secured to the lower edges of the doors, 75 and chains connected with said angle-bars and adapted to wind on the door operating shaft.

7. In a dumping car, the combination with 80 a frame and a hopper bottom, of side stakes secured to the same, an angle-beam connecting the upper ends of the side stakes at each side of the car, side doors hinged at their upper ends between the side stakes, means 85 for closing said doors and maintaining them closed, hinged floor plates adapted to cover the hopper bottom, and clamps attached to the angle-beams at the tops of the side stakes 90 for engaging said floor sections to hold the same in upright positions.

In testimony whereof, I have signed this specification in the presence of two subscribing witnesses.

ANTON BECKER.
